CLAIM

The ornamental design for a membrane filtration module, as shown and described.

DESCRIPTION

FIG. 1 is an isometric view of a first embodiment; FIG. 2 is a side elevation view of a first embodiment; FIG. 3 is a front elevation view of a first embodiment. FIG. 4 is a plan view from the top of a first embodiment. FIG. 5 is a plan view from the bottom of a first embodiment; FIG. 6 is an isometric view of a second embodiment; FIG. 7 is a side elevation view of a second embodiment; FIG. 8 is a front elevation view of a second embodiment; FIG. 9 is a plan view from the top of a second embodiment; and, FIG. 10 is a plan view from the bottom of a second embodiment.

The membrane filtration module is shown with a symbolic break in its length. The appearance of any portion of the article between the break line forms no part of the claimed design. The dot-dash line shown in FIGS. 1-3 and 6-8 indicate a boundary and form no part of the claimed design. The dash-dash lines in FIGS. 1-10 indicate portions of the article that form no part of the claimed design.
